[57] CLAIM

The ornamental design for an electrolytic capacitor, as shown and described.

DESCRIPTION

FIG. 1 is a front view of an electrolytic capacitor showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view from a view point at the right and above the electrolytic capacitor; and,

FIG. 8 is a perspective view from a view point at the right and below the electrolytic capacitor.
